UNITED STATES PATENT OFFICE.

VITTORIO ANDRIOLI, OF NEW YORK, N. Y.

BOILER CIRCULATING DEVICE.

1,403,534.

Specification of Letters Patent. Patented Jan. 17, 1922.

Application filed September 1, 1920. Serial No. 407,444.

To all whom it may concern:

Be it known that I, VITTORIO ANDRIOLI, a subject of the King of Italy, residing at the city of New York, in the State of New York, have invented certain new and useful Improvements in a Boiler Circulating Device; and I do hereby declare that the following is a full, clear, and exact description of the invention, such as will enable others skilled in the art to which it appertains to make and use the same.

The present invention relates to improvements in a boiler circulating device and has for its object certain very important improvements modifying my apparatus already described in my co-pending United States application filed April 29th, 1919, Serial No. 293,523.

An object of the invention is the provision of a boiler circulating device, in which a subdivision of water is obtained and in which the water will be brought into the fire box from opposite sides thereof by separate apparatuses which, however, function together and in which the water is equalized, when the water is injected from either the right or the left sides of the boiler. By this arrangement and subdivision, a more rapid increase in the circulating current of water in the boiler is obtained, and the water in the said boiler will be much more quickly heated.

Another object of the invention is the provision of means whereby a notable increase of the direct surface of heating represented by the several boiler tubes in the fire box, takes place, thereby increasing the evaporation action of heat on the water in contact with the said boiler tubes. The large increase of direct heating surface which comes to increase the fire box permits a considerable reduction of fuel, thereby making it possible to operate the boiler at a minimum cost.

Another object of the invention is the provision of means for increasing the direct heating surface, whereby the number of boiler tubes can be diminished, thus reducing the forced draft of the locomotive, eliminating a considerable amount of the necessary fuel now employed, and also conserving the fire box materially.

A still further object of the invention is the provision in a boiler such as above referred to, of two independent apparatuses for increasing and producing water circula-

tion, in which the water is equalized, levelled, and forced or fed into the fire box tubes from the collectors and subdivided into the various boiler tubes, the temperature 60 being above that of the boiler, thus avoiding in such manner any undesired difference in temperature.

Still another object of the invention is the provision in a boiler such as above referred to of novel water circulating means which will produce the greatest amount of boiler efficiency and which will be comparatively simple and inexpensive to manufacture, reliable and efficient in use, and readily 70 operated.

With the above and other objects in view, the present invention resides in the novel features of construction, formations, combinations, and arrangements of parts to be 75 hereinafter more particularly described, claimed and illustrated in the accompanying drawings, forming a part of the present application, and in which:

Figure 1 is a horizontal sectional view 80 constructed in accordance with the present invention and in which transverse boiler tubes are provided;

Figure 2 is a longitudinal sectional view, 85 showing a portion at the fire box end of the boiler in elevation;

Figure 3 is a horizontal sectional view taken through a boiler constructed in accordance with the present invention, in which longitudinal boiler tubes are provided; 90

Figure 4 is a longitudinal sectional view 95 of the device disclosed in Figure 3;

Figure 5 is a transverse sectional view taken through a fire box on the line 5—5 of Figure 2;

Figure 6 is a view taken on the line 6—6 of Figure 2;

Figure 7 is a similar view taken on the line 7—7 of Figure 2;

Figure 8 is a transverse sectional view 100 taken on the line 8—8 of Figure 1;

Figure 9 is a detail sectional view part in elevation illustrating one of the cages and methods of supporting the boiler tubes;

Figure 10 is a detail sectional view illustrating the means of supporting the ends 105 of the boiler tubes;

Figure 11 is a transverse sectional view taken through one of the collector tubes and its cover;

Figure 12 is a vertical sectional view there- 110 of partly in elevation; and,

Figure 13 is a transverse sectional view through one of said collector tubes and its cover.

Referring now to the accompanying drawings by corresponding characters of reference throughout the several views the numeral 1 designates in general a boiler which is shown in conventional form, the same comprising the usual cylindrical body portion 2 and fire box 3. The fire box 3 is surrounded by the usual crown side 4 of the boiler. As the customary boiler tubes form no direct part of the present invention, they are not shown in the drawings, 10 but the front and rear tube plates are designated at 5 and 6 respectively.

As shown in the drawings for purposes of illustration, a locomotive boiler is used, but it should be understood that I am not to 20 be limited to this particular type of boiler, but may apply the invention to a stationary boiler, or, in fact, to any other type of boiler, and I might modify the various parts of this invention so as to comply therewith 25 so long as the principle of the invention is not changed.

A pair, or row, or as many as may be desired, of collector tubes are employed. These tubes are shown at 7 and extend 30 parallel with the outer sides of the crown side 4 of the boiler on the outside thereof, and are encased by suitable coverings 8 which may be secured on the outer side of the boiler in any suitable manner. Suitable openings 9 are provided through which 35 these said tubes may pass. The forward ends of the tubes 7 are extended within the portion 2 in parallel relation and adjacent the opposite sides thereof, as shown at 10, 40 and are connected at their forward ends to a pair of boxes 11. These boxes are secured to the boiler in any suitable manner and have connected therewith the injector tubes 12. Tubes 13 extend from the forward 45 end of the boxes 11 in axial relation to the tubes 10 and have their terminals extended through the front plate 5.

Depended extensions, shown in dotted lines by the reference character 14, are provided at the rear of the plate 5, through which the water may flow upwardly into the boxes 11 from the boiler. These extensions 14 may be dispensed with, if desired, and pipes 15 may take their places. 50 The pipes 15 may be connected at the forward ends of the tubes 13 and pass through the plate 5, from whence they are extended downwardly and again pass rearwardly through this said plate into the bottom of the boiler for likewise directing the water upwardly and into said boxes.

As shown in Figure 6, two separate pipes 15^a may be employed, while, as shown in Figure 7, one single pipe 15^b may be used 65 if desired.

In order that the water brought forward to the collectors 7 may be kept at the same temperature as the boiler, suitable openings 22 may be provided in the crown side of the boiler, as clearly shown in Figures 70 1, 11 and 12 of the drawings. These openings may be in any desired number and arranged alternately between the tubes 20 and lead into the surrounding space formed within the cover 8, so that steam may pass 75 from the boiler into this surrounding space completely enveloping the collectors 7, thus keeping the water therein at the same temperature as that of the boiler.

The cover 8 may be provided at convenient points with removable plugs 16 which may be removed, when desired, for cleaning purposes.

Feeding pipes 17 extend from the collector pipes 7 into the interior of the fire box at 85 a slight downward slant, as clearly shown in Figure 5 of the drawings. These pipes 17 pass through cages 18 which may be attached to the sides of the fire box 3 and its crown side 4 by suitable packing devices 19 90 desired to hold the said cages firmly in position and also to support said fire box and crown side in their proper spaced relation.

The cages 18 support the outer ends of the heating tubes 20 which surround the feeding pipes 17 and extend inwardly into the fire box in spaced parallel and concentric relation to the said pipes 17. The lower ends of these tubes 20 may be secured to the walls of the fire box in any preferred 100 manner, such as shown in Figure 10, one manner being to reduce the ends of the tubes and extend them through both the wall of the fire box and the crown side, as shown at 21, or to provide a socket 22' in the ends 105 thereof which receives the balls 23 carried by the spacing pins 24 which pass through the walls of the said fire box and crown side, and which are attached thereto in any suitable manner.

Referring more particularly to Figure 3 of the drawings, the collector tubes are dispensed with and the ends of the tubes 10 are connected by a transverse collector tube 25 from which extend the before mentioned feeding pipes 17. These pipes 17, instead of being arranged transversely of the fire box, as shown in the remaining figures of the drawings, extend longitudinally therein at a slight downward incline. The cages 120 and remaining apparatuses of these two figures are identical with those shown in the remaining figures of the drawings, so a detailed description thereof is not deemed necessary.

The boxes 11 shown in the drawings are connected at their lower extremities by one or more tubes 26, so that when water is injected into the boiler either at the right side or the left side thereof, this water will be 130

levelled by the two apparatuses and the current existing in the tubes 13 forces this water directly into the fire box through the two apparatuses, where it is subdivided into 5 as many parts as there are tubes within the fire box, which provides for a very rapid rising of the temperature in the injected water, which is superior to the temperature of the water in the boiler.

10 As shown by the dotted lines particularly in Figure 5 of the drawings, as many tubes and pipes 17 as is desired may be placed in the fire box, but for the purpose of illustrating the principle of the invention, I 15 have only shown in full lines one row of such tubes.

As shown particularly in the device disclosed in Figures 1 and 2, the tubes 20 are arranged in staggered relation, each alternate tube being connected to the collector tube 7 upon the opposite side of the fire box.

In order to provide means for draining sediment from the boxes 11, suitable drain cocks 27 may be attached thereto, if desired.

In operation, the water which comes from the tubes 10 and 13 into the collectors 7 is introduced in the water tubes 17, subdivided in the various boiler tubes 20 placed 30 into the fire box, causing the temperature thereof to be immediately raised ahead of the temperature which exists in the boiler, and this water overflows from said tubes into the boiler through the open spaces in 35 the cages 18.

From the foregoing description taken in connection with the accompanying drawings, it will be manifest, that a circulating device for boilers is provided which will 40 fulfil all of the necessary requirements of such a device.

It should be further understood in this connection that various minor changes in the specific details of construction can be 45 resorted to within the scope of the appended claims, without departing from the spirit or sacrificing any of the advantages of the invention.

Having thus fully described the invention, what I claim as new and desire to protect by Letters Patent is:

1. The combination in a device of the character described, with a boiler having a fire box, cages attached to the fire box and 55 boiler and communicating with the interior of the boiler, collector tubes positioned at opposite sides of the boiler exterior of the fire box, feeding tubes communicating with the collector tubes and passing through the 60 cages into the fire box, heating tubes sur-

rounding the feeding tubes and carried by and communicating with the cages, and means for conveying water separately to the collector tubes from opposite sides of the boiler.

65

2. The combination in a device such as described, with a boiler including a fire box, a crown side for said boiler, collector tubes positioned exterior of the crown side of the boiler, coverings for the collector tubes secured to the crown side of the boiler, forming compartments surrounding said collector tubes, said crown side having openings therein providing access to said surrounding compartments from the interior of the boiler, cages connected to the fire box and crown side and retaining the same in normal position, said cages having communication with the interior of the boiler, feeding tubes communicating with the collector tubes and passing through said cages and through the fire box, heating tubes carried by the cages completely surrounding the feeding tubes and communicating with the interior of the boiler through said cages, 80 and means for conveying water to the collector tubes from the forward end of the boiler.

85

3. The combination in a device of the character described, with a boiler having a fire box therein, the crown side for said fire box forming a compartment between its inner surface and the outer side of the fire box communicating with the interior of said boiler, cages disposed in said compartment and secured at their ends to the fire box and fire box cover, said cages having communication with the interior of said boiler, collector tubes positioned exterior of the boiler and adjacent said cages, feeding 90 tubes communicating with the collector tubes and passing through said cages into the fire box and extending completely across the same, heating tubes carried by the cages and surrounding the collector 105 tubes, said tubes being inclined downwardly into the fire box, boxes positioned centrally of the boiler upon opposite sides thereof, tubes connecting the collector tubes and boxes, tubes extending from the boxes to the forward end of the boiler into which 110 water is fed from the boiler to said boxes, an equalizing tube connecting said boxes, and means for injecting water into the boxes from the outside of the boiler, substantially 115 as and for the purposes set forth.

In witness whereof I have hereunto set my hand.

VITTORIO ANDRIOLI.
